[57] CLAIM

The ornamental design for a hanger cover, as shown and described.

DESCRIPTION

FIG. 1 is a front elevational view of a hanger cover showing my new design;

FIG. 2 is a rear elevational view thereof;

The hanger cover is of conventional thickness and the cross line shading which is partially shown is understood to repeat uniformly across the circumscribed surface and to represent conventional fabric the broken line showing of the hanger hook is for illustration only.

FIG. 1

FIG. 2
